UNITED STATES PATENT OFFICE

99,827

DESIGN FOR A DISH

Samuel A. Scaman, Berwyn, Ill.

Application March 4, 1936, Serial No. 61,469

Term of patent 3½ years

To all whom it may concern:

Be it known that I, Samuel A. Scaman, a citizen of the United States, residing at Berwyn, in the county of Cook and State of Illinois, have invented a new, original, and ornamental Design for a Dish, of which the following is a specification, reference being had to the accompanying drawing, forming part thereof, and in which:

Fig. 1 is a top plan view of a dish showing my new design;

Fig. 2 is a perspective view; and

Fig. 3 is a sectional view along the line 3—3 of Fig. 1.

I claim:

The ornamental design for a dish, as shown.

SAMUEL A. SCAMAN.
